MUSICAL COMB CONSTRUCTION

Peter Ganine, Los Angeles, Calif.

Application May 18, 1956, Serial No. 585,826

4 Claims. (Cl. 84—94)

This invention relates to a new and improved musical comb and a new and improved method of making the same.

More particularly, the invention relates to such a musical comb and method as is particularly adapted for use in a music box or the like substantially corresponding to commercially available music boxes preferably of the Swiss type, but incorporating features of novelty and advantage referred to in my co-pending applications, Serial No. 393,694, filed November 23, 1953, and Serial No. 470,219, filed November 22, 1954, now Patent No. 2,838,834 of which the instant application is a continuation in part.

Music boxes known to the prior art have employed wires, reeds, flat or round, and other vibrating fingers having a free end and a secured end normally clamped or cast into a base itself comprising or in turn secured to a sounding board. Occasionally, the vibrating fingers or reeds were formed from a sheet metal section by die stamping, cutting, or trimming and filing the individual reeds by hand to achieve true desired tones. Hand trimming and filing are employed particularly in the production of the well-known Swiss musical tones designed for incorporation into Swiss music boxes commercially available throughout the world.

The Swiss musical combs are commercially acceptable in tonal quality but they have recently been unable to compete from a cost standpoint with the mass-produced combs of American manufacture which though they improve upon other prior art devices suffer from a somewhat inferior tonal quality relative to the Swiss music combs. The most popular current American product employs piano wires instead of the relatively flattened reed-like forms exemplified by the Swiss type comb.

It has long been thought that the sheet formed combs generally analogous to the Swiss type combs and made from a sheet of springy material would have a wide market and satisfy a long felt need if they could be produced by satisfactory economical mass production methods without unduly sacrificing accuracy of tone. Consequently, numerous efforts have been and are being made in the United States and elsewhere to achieve a musical comb construction of commercially acceptable tone quality by means of economical and accurate mass production methods. Thus far, however, no successful die stamped sheet metal or other mass produced comb has been developed which is capable of matching the hand tuned qualities of the Swiss musical combs.

More specifically, mass production has failed to achieve a sufficiently accurate cutting or forming of the vibrating teeth or reeds to give a commercially acceptable tone and especially has mass production failed to evolve such a comb consistently and repeatedly during production. This has largely been due to the inability to cope with those slight variations and tolerances in the cutting or forming of the teeth which are immediately reflected in variation and impairment of the desired true tone of the teeth.

2

Considerable difficulty, on the other hand, is encountered in initially cutting the teeth for a metal-stamped comb when the casting operation follows the cutting of the teeth. Die costs are high, and since the mating die surfaces are critical, undesirable flash forms at the parting line of the die and around the teeth of the comb. Also, material tolerances, alone or when combined with necessary die tolerances, are an invitation to variations, flash and other difficulties which impair the resultant desired purity and uniformity of tone.

5 While it is advantageous to cut the pluckable teeth from untempered stock when such teeth are formed from steel, any tempering by heat following the cutting of the teeth deforms or alters the shape or structure of the teeth in a manner to change the resulting tone in undesirable and unpredictable ways. By the instant invention the teeth are advantageously slot-formed from untempered stock, then tempered while in a continuous ribbon so as to minimize tooth warpage, and thereafter the teeth are cut to proper length or tone.

10 In view of the above considerations, among others, it is an object of this invention to provide an economical and acceptably accurate new and improved comb and method for manufacturing the same on a commercial mass production basis which will as closely as possible approximate the accuracy and quality of hand tuned musical combs now commercially available but at appreciably higher manufacturing cost and consumer prices.

Another object of the invention is to provide a new and improved die formed musical comb of the desired character described wherein the various teeth will render substantially true reproduceable tones or sequences of notes in a pre-selected musical scale or portion thereof.

15 Another object of the invention is the provision of such a new and improved musical comb in which the individual teeth will vibrate without interference with or from the oscillation of adjacent teeth. Yet another object of the invention is the provision of such a new and improved musical comb of relatively low cost and high quality which lends itself to mass production by means of the new and improved methods herein disclosed.

20 Another object of this invention is the provision of a new and improved continuous method for the efficient and effective manufacture of musical combs of the desired character described.

25 Another further object of this invention is the provision of appropriate commercial procedures and methods for casting a base integrally with a sheet of resilient comb stock and cutting the teeth of a musical comb from such comb stock with such accuracy and efficiency as to permit the satisfaction of a long felt want therefor.

30 Yet another object of this invention is the provision of a new and improved musical comb and method of making the same to such an excellent standard of tonal quality as will compare favorably with prior art hand tuned devices of analogous character.

35 It is moreover among the objects of this invention to provide a new and improved means and method for achieving the herein stated objects and to provide improvements over prior art devices and methods heretofore intended to accomplish generally similar purposes.

40 Other objects and purposes will become apparent from the following description considered in the light of the accompanying drawings wherein like parts are illustrated by like reference numerals.

45 In the drawings:

50 Figure 1 is a plan view of a preferred form of music box incorporating a comb embodying this invention and made by the method of this invention.

55 Figure 2 is a vertical sectional view of said music box of Figure 1.

Figure 3 is a diagrammatic side elevational view showing an apparatus for the continuous production of musical combs of this invention from a roll of sheet comb stock.

Figure 4 is a sectional view taken longitudinally through two cutting dies showing punching knives after having cut slots through sheet stock to cut teeth therein.

Figure 5 is a sectional view taken as on a line 5—5 of Figure 4.

Figure 6 is a similar sectional view taken as on a line 6—6 of Figure 4.

Figure 7 is a partial plan view showing a portion of sheet stock after it has been punched and slotted.

Figure 8 is a plan view of the interior of a mold, one-half being removed showing the same as it would appear on the parting line thereof.

Figure 9 is a perspective view showing a cut-off produced in an advanced stage of the method of this invention.

Figure 10 is a perspective view showing a completed comb embodying the invention.

Figure 11 is a fragmentary detail plan view of the comb of Figure 10.

Figure 12 is a fragmentary detail perspective view of the comb of Figure 10.

Referring more particularly to the drawing which set forth by way of illustration but not limitation a comb and method of making the same embodying this invention, I first describe generally a music box environment for the comb of this invention in order to indicate an operative environment therefor.

In said drawings a comb 10 comprises a cast base 11 is operatively mounted as on the bottom 12 of a frame defining a music box housing. Such securement of the comb may be as by means of a bracket 13 or the like secured as by rivets or integrally cast as a unit with the base 11 of the comb which in turn is firmly or integrally correspondingly affixed to the bottom 12.

Likewise supported on the bottom 12 of the music box is a cylindrical drum 14 having external gear teeth 16 formed around its lower end. The drum 14 is adapted for rotation relative to the frame and bottom 14 by a pinion 17 keyed to the end of a shaft 18 appropriately journaled in the bottom 12. The shaft 18 includes a suitable crank and handle 19 and 21, respectively. A wire 22 may be wrapped several times around the shaft 18 and may have a free end forced through an aperture through the bottom 12 and bent on the inside of the bottom to retain the wire in position. The wrapping of the wire 22 about the shaft 18 provides a desired clutching action to permit free rotation of the shaft 18 in a pre-determined direction but to resist counter rotation thereof.

Also supported on the bottom 12 is a cylindrical shell 23 comprising a portion of the frame of the music box. Such shell 23 may be secured to the bottom 12 as by screws 24. Such shell 23 serves to journal the cylindrical drum 14 for rotation therein and relative to the bottom 12. Said shell may be of any desired height or may be omitted altogether in accordance with the teachings of my earlier filed co-pending application above referred to.

In the instant embodiment, however, and fixedly held within the cylindrical drum 14 is a cylindrical band 28 optionally releasably held as by means of bosses 26 and 27 formed on the drum 14. The band 28 is provided internally with a series of plucking protuberances 29 which preferably are formed on the band 28 by punching the material forming the projections 29 inwardly. The arrangement and sequence of the protuberances 29 are such that depending upon the pitch and arrangement of the various teeth of the musical comb, a pre-selected melody can be played in a manner well known to those skilled in this art.

The cylindrical band 28 is preferably removable from the cylindrical drum 14 so that other band members may

be substituted readily and thereby provide for a variety of different tunes to be played upon the same music box and comb.

Having thus described generally an optional form of music box adapted to receive the comb of the instant invention, I will now describe in more detail the comb itself and the method of making the same which again by way of illustration and not of limitation comprise the herein described and claimed invention.

The prior art now knows the continuous feeding of wires into a mold and the forming of a casting around the ends of the wires in the mold followed by the ejection of the casting which draws additional lengths of wire into the mold for successive corresponding molding, cutting and withdrawing steps. I have adopted a continuous method as shown particularly in Figures 3 through 9 for the optional formation of my improved comb. This method comprises providing a long strip or ribbon of sheet stock 31 and feeding the same through a punch station 32, preferably integral with the cutting dies where casting holes 33 are cut (Figure 7) and where accurate preferably separate locating holes 34 are punched through the sheet stock in transverse and longitudinal relationship to one another along said strip for positively and accurately fixing and holding the ribbon.

The punched portion of sheet stock 31 is fed to a slotting station 36 comprising a die made up preferably of two halves such as 37 and 38, to prevent undue stress on the mat and which might cause the resultant strips of reed-forming at the die to be distorted by the cutting action. Thus alternate cuts are advantageously made so that intermediate cuts, for example, are skipped on the first die-cutting action and the intervening cuts are made in a second die-cutting action.

Means (not shown) are connected to the die halves 37 and 38 cyclically to open and close the same. When the die halves are closed they are held in registry by alignment pins 39 of die half 37 fitting in holes in die half 38, and also and particularly by some of the locating pins 40

40 cutting and fitting snugly in guide holes 34 of sheet stock 31 and also snugly fitting into corresponding holes in die half 38. Thus the sheet stock is held in definite fixed relationship with the die halves while the die halves are held closed in accurate registry with each other.

45 In this closed position of the die halves, knife guide slots 41, formed in parallel relationship in the die half 37, are in precise alignment with corresponding knife guide slots 42 in die half 38. A plurality of preferably alternate knife punches 43, mounted as in a movable die

50 holder 44, for slideable, carefully guided reciprocal movement within the die guide slots 41 and 42 are forced downwardly through an oriented section of sheet stock 31 to form parallel spaced slots 46 (Figures 6 and 7). The slots 46 are spaced in predetermined relationship to 55 accommodate for example, a second set of other parallel spaced slots 47 in alternating relationship with slots 46. This multiple stage cutting operation takes place while the dies are firmly closed, and all parts between the die halves are securely held. Thus lateral displacement of the slot-formed stock is minimized.

In this connection, it is of particular importance to note that the respective knives 43 have flat bottom edges and that the knives fit accurately within the slots 41 and 42 of the respective die halves. It is also important to 60 note that the section of sheet stock 31 as a whole is firmly held between the die halves and against an edge-engaging shoulder 50 so as to resist any tendency to cause the same to shift.

Said bottom edge 51 of the respective knives 43 is 65 slanted as shown most clearly in Figure 4. Thus, one edge 52 of the knives is sharp and constitutes a leading edge. It is important to note, as seen most clearly in Figure 5, that the sheet stock section 31 is firmly supported as stated on spaced shoulders 53 and 54 on the 70 respective die halves 37 and 38 and these can be in-

dividually spring loaded at their stock-engaging ends to compensate for any surface irregularities of the stock. When the knives 43 descend their first point of contact is with the sheet stock 31 immediately adjacent, and preferably in touching relationship to a sinuous or stepped inner confronting edge 52 (Figure 7) of the section of sheet stock 31. As the knives continue their descent they shear and cut the grooves 46 simultaneously but in a direction away from the edge 52. The essential support of the blank against the cutting thrust of the knives 43 is upon the shoulders 54 which in spaced relationship along the face of the die half 38 provide, with respect to each slot 46 cut in the blank, parallel opposed shoulders, firmly and accurately locating the knives and sustaining their thrust.

Thus as the blank is cut to form the slots 46, the sheet of metal comprising the same is supported with respect to each knife 43 along two spaced parallel shoulders 65. There is no opposing pressure against the knife thrusts except along lines parallel to the proposed slots 46 which are cut progressively from one end. Since these are cut and started at their bases and since their longitudinal shear is along parallel lines, starting from the bases of the proposed teeth exceeding accuracy is obtainable in defining the desired pre-determined widths of the respective teeth of the finished comb. The combined action of the progressive cutting from the bases of the teeth, the accurate and firm securement of the locating pins, and the continuous nature of the ribbon held firmly at spaced stations and along its edge on at least one side by the shoulder 50 on the die tends to promote utmost accuracy of dimensions between successive combs and between successive teeth of the same comb.

As is known in this art, the last shortest reed 55 (Figure 10) is not a working reed and may therefore be truncated. The guide shoulder 50 on the die is therefore placed along the edge of the stock 31 corresponding to the longest outer tooth 55'. Thereby such longest outer tooth 55' will be accurately guided against the die shoulder 50 while variations in width of the ribbon 31 due to manufacturing tolerances will be incorporated in the last short tooth 55 or cut off as a part of a final slot (not shown) without affecting the desired resultant and accurately cut working teeth remaining.

After the slots 46 have been cut in the sheet stock section, the knife punches 43 are again moved upwardly and die halves 37 and 38 are opened as at the beginning of the cycle and slots 47 of predetermined width and orientation depending on the intended design and tune of the comb, are cut between each pair of slots 46.

As stated, all of the slots 46 and 47 can be cut in a single slotting stage or in three, or more stages, at the same slotting station by means of alternate knives or at longitudinally spaced stations, if desired. The number of stages employed will depend upon such factors as the nature, thickness and composition of the sheet stock material, the efficiency of the knife punches 43 and the like considerations.

In view of the stated desirability of supporting and shearing along laterally spaced parallel shoulders 54, it is possible to form the comb species of my co-pending applications above referred to with great accuracy by the instant method. It is also possible and with what I believe to be greater individual tonal fidelity without blending of the vibrations of adjacent reeds to form a musical comb in the manner described above when the inner ends of the slots forms a striplike or sinuous outline whose configuration govern the length of the reeds and their respective pitch.

After all of the slots 46 and 47 have been cut into the sheet stock section and before cutting off the respective combs, the stock where a suitable temper, designed to produce the desired degree of resilience and tonal quality

in the final comb is produced in the slotted sheet stock section. The design and conditions of operation of tempering station 51 will depend upon the composition of the sheet stock material. High carbon steel is preferred for the sheet stock material but other suitable spring materials such as beryllium copper may also be used. In any event, the tempering operation will be continuously carried out in station 51 by the employment of any appropriate known heating and/or cooling operations.

10 A properly tempered, slotted ribbon portion in question then is moved to a casting station 53 where it is fed into a mold. The two sides 54 and 56 of the mold are closed against one another as guided on guide rods 57. After closing the mold, die casting metal is forced under pressure around the unslotted portion of the sheet metal stock section into the casting holes 33 and into an accurately formed molding cavity to form the base of the musical comb and a confronting adjacent tooth-forming stepped or sinuous confronting edge stock portion, or base portion. The casting is so carried out and the casting die halves 54, 56 are so formed that a narrow ledge 57' is formed between the casting 58 and the confronting inner ends of the slots 46, 47. Such displacement of the casting outwardly and laterally of the ribbon formed comb section and the consequent formation of said ledge 57' prevents the occurrence of flash from the casting which would interfere with the tone of the comb or its respective teeth. If the width of the ledge 57' is kept at a practical minimum, say of the order of $\frac{1}{64}$ ", the tone of the comb is not impaired and the vibration of one tooth will not affect the others. Thereby also the accuracy of the slotting operation is unimpaired by the usually less accurate casting operation, when required.

15 Ejection of the casting optionally in the direction of the arrow in Figure 8 against the knife 59, for example, as a cut-off stop in a subsequent stage of the comb forming operation will in the use of the instant continuous 20 method be accompanied by the shifting of the entire sheet stock 31 in said direction of the arrow to bring a fresh portion of the ribbon corresponding to another comb blank into the mold.

When desired, the cast base 58 is also made to surround and cover the edge of sheet stock 31 cut by the knife 59, by casting the base 58 thereover following the cutting operation at the knife 59.

The casting 58 forming the base is now firmly secured on the slotted and tempered sheet stock section and such 25 securement is enhanced by the provision of the casting holes 33 or other openings cut into the sheet stock 31 prior to the molding operation, as described above, through which holes the die cast body is continuous from side to side of the comb blank thus formed. Now the 30 sheet stock 31 is cut as by means of said knife 59 to sever a comb cut-off 61 as at the casting (Figure 9). The cutting operation accomplished by the knife 59 may be made in connection with the mold 53 but the cutting of the teeth to produce the finished comb 10 from the cut-off 61, when necessary for greater accuracy comprises a 35 separate accurate cutting operation accomplished on a separate accurate cutting and tuning die or by reference to and with the end of the guide holes 34 at said knife 59.

It is preferable in the practice of the instant invention 40 to form a stepped base wherein the individual reeds enter or emerge from the cast base at individual stepped parallel planes in the casting normal to the axis of the respective reeds.

The form of comb of Figure 12 embodies such a stepped 45 construction. In said Figure 12 the cast base is designated by the numeral 62; the individual teeth by the numeral 63; the holes in the blank by 64; and the perpendicular steps normal to the respective reeds by the numeral 66. In the form of comb shown in Figure 12 the side 50 edges there shown of the reeds 63 at the casting lie in

planes spaced tightly from but parallel to the side edges 67 of the steps 66.

The base 11 should be formed of a castable material whose melting point, when considered with the molding pressure, will be insufficiently high to affect the desired temper of the sheet of resilient material or blank around which it is formed. Within these limitations the comb forming material, while preferably of a spring-like material such as high carbon steel, beryllium copper, may be as stated of other springy substance such as spring steel, or the like. A zinc alloy of commercially acceptable quality for forming castings in commercial practice has been used to advantage, particularly with sheets of high carbon steel and of beryllium copper.

This invention features the provision of a new and improved die cast stamped melody comb having a metal body, preferably sheet metal, molded integrally with a castable base preferably of zinc alloy, thereby combining the best features of maximum surface displacement of air and form of the Swiss musical combs with desirable mass production methods of the character disclosed and claimed to fulfill the purposes of the objects herein stated.

While I have herein shown and described the invention in what I have conceived to be the most practical and preferred embodiment, it is recognized that departures can be made therefrom within the scope of my invention, which is not to be limited to the details disclosed herein, but is to be accorded the full scope of the claims so as to embrace any and all equivalent structure.

Having described my invention, what I claim as new and desire to secure by Letters Patent is:

1. A musical comb comprised of a comb element and a base element, said base element having an inclined edge and an edge opposite said inclined edge, the comb element being centrally embedded in the base element to be integral therewith and to extend outwardly therefrom

centrally from said inclined edge thereof, said edge being at an angle to the opposite edge of the said base, said inclined edge being provided with a plurality of step sections corresponding in number to the number of teeth in

5 the comb element and said comb element consisting of a sheet metal base having a plurality of parallel spaced teeth on one end thereof, each of a determined width and having a graduated varying length from one side edge of the comb element to the other but with the outer ends of 10 the teeth lying in the same plane substantially parallel to the outer edge of the comb base, and with the inner ends of the comb teeth lying in a plane angularly disposed to said outer edge of the comb base, the sheet metal base part of said comb element being embedded within the 15 said base element to within a short distance of the inner ends of said comb teeth.

2. The musical comb of claim 1, said sheet metal base with its comb teeth being comprised of a hardened and tempered steel alloy.

20 3. The musical comb of claim 1, said base element being comprised of a cast metal composition.

4. The musical comb of claim 1, said sheet metal base of said comb element having a plurality of openings therethrough and through which extend the said base 25 element.
